(57) **CLAIM**

The ornamental design for a wireless camera, as shown and described.

DESCRIPTION

FIG. 1 is a top, front and left side perspective view of a wireless camera showing our new design;

FIG. 2 is a left side elevational view thereof;

FIG. 3 is right side elevational view thereof;

FIG. 4 is a front elevational view thereof;

FIG. 5 is a rear elevational view thereof;

FIG. 6 is a top plan thereof; and,

FIG. 7 is bottom plan view thereof.

The portions of the camera in broken lines are shown for illustrative purposes only and form no part of the claimed design.
